UNITED STATES PATENT OFFICE.

WINFRED T. POWELL, OF CHICAGO, ILLINOIS, ASSIGNOR TO AUTOMATIC ELECTRIC COMPANY, OF CHICAGO, ILLINOIS, A CORPORATION OF ILLINOIS.

SELECTIVE SIGNALING SYSTEM.

1,306,716.

Specification of Letters Patent. Patented June 17, 1919.

Application filed August 23, 1916. Serial No. 116,482.

To all whom it may concern:

Be it known that I, WINFRED T. POWELL, a citizen of the United States of America, and a resident of Chicago, county of Cook, 5 and State of Illinois, have invented certain new and useful Improvements in Selective Signaling Systems, of which the following is a specification.

My invention relates in general to selective signaling systems but is concerned more particularly with automatic party line systems which are provided with so-called ring-back apparatus by means of which a calling subscriber may signal a called subscriber on 10 his own line. In the patent to Hovland, #1,158,221, there is described a system of handling reverting calls in bridged automatic party line systems, in which the calling subscriber, by manipulating his dial in 15 accordance with the proper digits, operates a frequency selecting switch at the exchange, which switch selects simultaneously the two frequencies of ringing current which correspond to the calling and called substations.

20 The calling subscriber then hangs up his receiver, whereupon mechanism in the frequency selector is put into operation to effect the application of the two selected ringing currents to the calling line alternately. The 25 called subscriber is thus signaled as usual; while the calling subscriber is also signaled so that he may know that the operation is proceeding in the proper manner, and also that he may be apprised of the response of the 30 called subscriber by the cessation of the ringing operation which occurs as soon as the called subscriber removes his receiver. The calling subscriber will then remove his receiver also and converse as desired.

35 The Hovland system is adapted to handle calls from any one of four bridged substations to any one of the remaining three, there being provided the usual four frequencies of ringing current. The object of 40 the present invention is to provide a reverting call signaling system in which the usual four frequencies of ringing current are used to selectively signal at the same time any two of eight substations on the same line, the 45 ringers being connected four from one side of the line to ground and four from the other side of the line to ground.

50 Because of the fact that the ringers are not bridged across the line and because 55 furthermore there are on each line two sub-

stations which respond to each frequency of ringing current, a new circuit arrangement and method of operation have been found necessary to save excessive complications, all of which will be described and explained 60 hereinafter, reference being had particularly to Figures 1 and 2 of the drawings which show diagrammatically an eight party telephone line and the necessary central office circuits and apparatus. Fig. 3 is a chart 65 showing the telephone numbers corresponding to all possible two station combinations on an eight party line.

Referring to Fig. 1 of the drawings, I have indicated by reference characters 11 70 and 12 a party line provided with eight substations which are indicated by reference characters A' to A⁸, inclusive. Substation A', which is representative of the group, comprises essentially the receiver 2, transmitter 75 3, switch hook 4, ringer 5, and condenser 6. Being an automatic substation there is also provided a calling device comprising a pair of impulse springs 7 and 8 controlled by the impulse cam 9 through the medium of 80 a finger hole dial (not shown). A calling device of suitable design is shown and described in the British patent to S. G. S. Dicker, #29,654 of 1910. When the receiver 85 is on the hook it will be seen that the ringer 5 is connected from the line conductor 12 to ground. The substation A⁶ is similar to substation A' but the ringer 5' is connected from line conductor 11 to ground. In order to save space only the ringers of the remaining six substations have been shown, three 90 of which are connected from line conductor 11 to ground and the other three from line conductor 12 to ground.

95 It has been found desirable in practice to use ringing currents of frequencies approximating 16, 33, 50, and 66 cycles per second. In accordance with this plan the ringers at substations A' and A⁶ are adapted to respond to the 16 cycle ringing current, the 100 ringers at substations A² and A⁶ to 33 cycle ringing current, the ringers at substations A³ and A⁷ to 50 cycle ringing current, and the ringers at substations A⁴ and A⁸ to the 66 cycle ringing current.

105 At the exchange the line conductors 11 and 12 are terminated in an individual line switch C, which is of the general type of line switch disclosed in British patent to James #26,301 of 1906; being, however, 110

more nearly of the particular type disclosed in U. S. Letters Patent #1,078,690, granted Jan. 17, 1912, to Frank Newforth. Since line switches of the foregoing type are well known in the art no extended description will be given. It will suffice to say that through the medium of line switch C the party line shown is given access to a plurality of selector switches one of which is shown and is indicated by reference character E.

The line switch C, together with a plurality of similar line switches, is controlled in its selective operation by means of the master switch D, which is of the general type of line switch disclosed in the above mentioned patent to James; being, however, more nearly of the particular type disclosed in British patent to Martin, #1419 of 1910. The function of the master switch, as is well known, is to maintain the plungers of all the idle line switches which it controls in position before the terminals of an idle trunk line.

The selector switch E is of the general type of selector switch disclosed in U. S. Letters Patent #815,321, granted March 13, 1906, to Keith, Erickson, and Erickson; being, however, of the particular type disclosed in the British patent to the Automatic Telephone Mfg. Co., #2543 of 1914. A selector switch of the foregoing type is operable in response to the first digit of a called number to select one of a plurality of groups of trunk lines, after which the selector operates automatically to select an idle trunk line in the selected group and extend connection thereto.

The selector switch E, in common with similar selectors, has access through certain of its bank levels to other selectors (not shown) by means of which connections may be extended toward the lines of other subscribers in the exchange, and it also has access through a separate bank level to a group of so-called frequency selectors, one of which is shown at F (Fig. 2).

The frequency selector F is a vertical and rotary directly controlled switch and is similar in mechanical construction to the switch shown in U. S. Letters Patent #815,176, granted March 13, 1906, to Keith, Erickson, and Erickson. The circuits are modified, however, to adapt the switch to the two-wire system of control as shown in the Newforth U. S. Patent #13,901, re-issued April 18, 1915, and are further modified to provide for the more comprehensive ringing operations which have to be performed. A still further modification lies in the provision of four wipers instead of three and the omission of the upper or private bank. The wipers are mounted on the shaft in two sets which are spaced apart a distance equal to the space between five bank levels.

It follows that when the lower set of wipers is in engagement with a set of bank contacts in the first level the upper set of wipers will be in engagement with the corresponding set in the sixth level, and when the lower set of wipers is in engagement with a set of bank contacts in the second level the upper set of wipers will be in engagement with the corresponding set in the seventh level, etc. From these considerations it will be seen that the frequency selector bank is for practical purposes divided horizontally into two sections, that the switch shaft is operable for five vertical steps instead of ten, and that when the shaft is rotated corresponding contacts in the upper and lower halves of the bank will be selected simultaneously.

The lower five levels of the frequency selector bank have certain of their contacts connected in suitable manner to the four ringing current generators R', R², R³, and R⁴, whereby selection of the proper ringing currents may be accomplished through the medium of the wipers 123 and 124. The three interrupters I', I², and I³, which are mounted on a common shaft, are suitably connected to the proper bank contacts in the upper five levels, thereby providing means for controlling via the wipers 121 and 122 the application of the selected ringing current, or currents, to the calling line.

The necessity for the simultaneous selection of ringing currents and controlling circuits therefor may be seen from a more detailed consideration of the functions the frequency selector has to perform. In broad language the frequency selector must be provided with means whereby any one of the eight subscribers on a calling line, the line 11-12 for example, may ring his own bell and the bell of any other subscriber on the same line alternately. Because of the arrangement of the substation ringers, two to each ringing current frequency connected on opposite sides of the line to ground, there arises four different conditions under which the signaling must be accomplished. The chart Fig. 3 shows every possible combination with the necessary telephone numbers and these different combinations are arranged in four groups according to the signaling operation required. Briefly stated, the first group includes all calls in which only one ringing current generator is selected and which is applied to the two sides of the calling line alternately; the second group includes all calls in which two generators are selected and applied alternately to one side of the calling line; the third group is similar to group two except that it relates to the other side of the calling line; while the fourth group includes all calls in which two generators are selected and applied alternately one to one side of the calling line and the

other to the other side. Means are provided in the frequency selector F for reversing the incoming line and for switching from one selected generator to the other, which means 5 comprise the relays 114 and 115. These relays together with a ringing relay 113 are controlled by the three ringing interrupters I'-I³, inclusive, to produce the desired results, all in a manner which will be fully 10 explained hereinafter. For the purposes of this explanation, it will first be assumed that the subscriber at substation A' desires to signal the subscriber at substation A⁵, this being the connection illustrated in the drawings. 15 Afterward connections representative of the other ringing conditions will be briefly described. Inasmuch as a large portion of the automatic equipment used is old and well known in the art, having been fully 20 described in the publications referred to, the operation will be described in a more or less general manner except where it has to do with the principles of the invention.

When the calling subscriber at substation 25 A' removes his receiver to initiate the call, an energizing circuit is completed over the line conductors 11 and 12 for the line relay 14 of the line switch C. Upon attracting its armature, the line relay 14 closes a circuit 30 for the pull-in winding 18. Upon energizing, the pull-in winding operates both the plunger arm 15 and the cut-off armature 16; the former through the medium of its plunger (not shown) forcing the bank springs 35 30-33, inclusive, into engagement, respectively, with contacts 34-37, inclusive; and the latter disconnecting the line conductors 11 and 12, respectively, from ground and from the line relay 14. By the engagement 40 of bank springs 30 and 33 with contacts 34 and 37, respectively, the line conductors 12 and 11 are extended through normally closed contacts of the switching relay 63 to the double-wound line relay 50 of the selector E. 45 The line relay 50 is accordingly energized over the loop circuit including substation A' and, upon attracting its armature, closes a circuit for the slow-acting release relay 51. Upon energizing, the release relay closes a 50 holding circuit for the line switch C which may be traced from ground G⁵ by way of contact springs 65, contact 35, bank spring 31 and the holding winding 17 to battery B. Since the line relay 14 is slow-acting, it retains 55 its armature to maintain the pull-in winding 18 energized until after the above holding circuit has been established. A branch of the holding circuit extends by way of conductor 20 to multiple test contacts in 60 the banks of connector switches having access to the line of substation A' where by a ground potential on these test contacts the said line is made busy. By the engagement of bank spring 32 with contact 36 a circuit 65 is closed whereby the master switch D is op-

erated in the well known manner to advance the plungers of all the remaining idle line switches into position before the terminals of the next idle trunk line.

The foregoing operations whereby the 70 line conductors 11 and 12 have been extended through to the line relay 50 of the selector E have taken place in response to the removal of the receiver at substation A. A reference to the chart (Fig. 3) will show 75 that the number which it is required to call is 021. The calling subscriber will therefore now manipulate his dial in accordance with the first digit 0 of the desired number, thereby separating momentarily the impulse 80 springs 7 and 8 ten times and interrupting each time the circuit of line relay 50 of selector E. As a result of these interruptions of its circuit the line relay 50 is deenergized 85 a corresponding number of times, sending an impulse at each deenergization from ground at G⁶ to the slow-acting relay 62 and the vertical magnet 65 in series. The vertical magnet, in response to these impulses, steps up the switch shaft until the wipers 90 70, 71, and 72 stand opposite the horizontal level in which are located contacts which are terminals of the group of frequency selectors. The relay 62, being slow-acting, retains its armature during the series of impulses and closes a circuit for the test relay 64, which latter relay prepares a circuit for the rotary magnet 66 and locks itself to ground at G⁵. At the end of the series of 95 impulses the relay 62 deenergizes, thereby 100 completing the aforementioned circuit of the rotary magnet 66, whereupon the wipers 70, 71, and 72 start rotating in search of an idle trunk line. As is well known, the rotary magnet interrupts its own circuit and also 105 the locking circuit of the test relay at every energization, the contacts in the latter circuit, however, being short-circuited by the test or private wiper 71 while passing over grounded busy contacts. As soon, therefore, as the test wiper 71 arrives at an underground test contact the test relay 64 deenergizes and opens the rotary magnet circuit, thereby bringing the wipers to rest upon the terminals of an idle trunk line, 110 115 assumed to be in this case the contacts 73, 74, and 75. As a further result of the deenergization of the test relay 64, a circuit is completed for the line switching relay 63 which relay, upon energizing, disconnects the extended line conductors 12 and 11 from the windings of the line relay 50 and further extends them by way of wipers 70 and 72, bank contacts 73 and 75, and trunk line conductors 180 and 181 to the double-wound 120 line relay 100 of the frequency selector F.

The line relay 100 thereupon energizes over the line circuit extending back through substation A' and completes an energizing circuit for the slow-acting relay 101. Re- 130

- lay 101, upon attracting its armature, prepares a circuit for the vertical and rotary magnets 104 and 105 and also completes a new holding circuit as follows: ground at 5 G¹⁰, contact springs 119, bank contact 74 and wiper 71 to wire junction 80, where the circuit divides, one branch extending by way of a back contact of relay 64 through the winding of line switching relay 63 to battery 10 B, and the other branch extending by way of off-normal contact 67 and interrupter contact 81 to wire junction 82 where it joins the previously described holding circuit extending back to the line switch C.
- 15 The subscriber at substation A' may now operate his dial in accordance with the second digit 2 of the desired number, resulting now in deenergizations of the line relay 100 of the frequency selector F. At each de- 20 energization the line relay 100 sends an impulse from ground at G¹¹ to the slow-acting relay 107 and the vertical magnet 104 in series, side switch wiper 115 being in its first position. The vertical magnet, in response 25 to these impulses, steps up the shaft until the upper and lower sets of wipers stand opposite, respectively, the seventh and the second horizontal levels of bank contacts. Relay 107, being slow-acting, retains its 30 armature during the series of impulses and maintains a circuit from ground at G¹² for the private magnet 108. At the end of the series of impulses, the relay 107 deenergizes and breaks the circuit of the private magnet, 35 which latter controls the side switch wiper 115 in the usual manner to advance it to its second position.
- The subscriber at substation A' may now 40 operate his dial in accordance with the third and final digit 1 of the desired number, resulting now in a single deenergization of the line relay 100. Side switch wiper 115 being in its second position, the line relay in response thereto sends an impulse to the slow- 45 acting relay 107 in series with the rotary magnet 105. The rotary magnet operates in response to this impulse to rotate the upper wipers 121 and 122 and the lower wipers 123 and 124 until they engage the 50 first sets of bank contacts in the respective levels to which they have been raised. The relay 107 and the private magnet 108 are energized during the last series of impulses as before, the latter upon deenergizing, again controlling the side switch wiper 55 115 to advance it to its third position.
- The foregoing operations of the frequency selector are practically identical with the operation of the connector described in the 60 above mentioned Newforth patent. The remaining operations will be described with considerable more detail. Having operated his calling device to perform the necessary selective operations at the exchange, the 65 calling subscriber at substation A' will now

hang up his receiver, thereby again breaking the circuit of the line relay 100. Upon deenergizing, the line relay completes a circuit for the switching relay 112 over the following path: ground at G¹¹, closed contacts of 70 line relay 100, contact springs 120, winding of relay 107, contact springs 131, winding of relay 112, and side switch wiper 115 (in third position) to battery B. Relay 107 is not energized. Relay 112, upon attracting its armature, first completes a circuit by which the slow-acting release relay 101 may be kept energized independent of the line relay 100 and which may be traced as follows: ground at G¹⁴, contact springs 132, 80 and winding of relay 101 to battery B. As a further result of the energization of relay 112 the incoming trunk line conductors 180 and 181 are disconnected from the windings of the line relay 100 at contact springs 146 85 and 149, respectively, and are connected instead by way of contact springs 144 and 147 to the contact springs 135 and 138 of the ringing relay 113. Finally, assuming that the interrupter I' is in the position shown, 90 a circuit is completed for the ringing relay 113 as follows: ground at G¹⁶, interrupter I', conductor 150, contact springs 133, and winding of relay 113 to battery B.

Upon the energization of the ringing relay 113, a circuit for the generator R' is completed as follows: ground at G¹⁷, generator R', upper contact 2 up and 1 in, wiper 123, contact springs 161 and 162, contact springs 166 and 165, contact springs 137 and 138, 100 contact springs 147 and 148, trunk line conductor 181 to bank contact 75, thence by way of wiper 72, contact springs of switching relay 63, bank contact 37, spring 33, line conductor 11, and ringers of substation A⁵, A⁶, 105 A⁷, and A⁸ in parallel to ground, and thence back to ground G¹⁷, the starting point. Upon the closure of the above circuit, the ringer at substation A⁵, which is the ringer corresponding to the frequency of generator 110 R', responds to thereby notify the subscriber that he is wanted. After a brief interval the ringing relay circuit is broken by the rotation of the interrupter I' and the said ringing relay deenergizes. It will be observed 115 that the interrupter I' has two live segments, providing for two ringing periods at each complete revolution, while the interrupters I² and I³ have but one live segment each. It follows, therefore, that in 120 the second half of the revolution of the interrupter shaft the circuit of the ringing relay 113 will again be completed. Also at the same time or an instant before the following circuit is completed by interrupter 125 I², ground at G¹⁸, interrupter I², conductor 152, upper bank contact 7 up and 1 in, wiper 121, contact springs 171 and 170, and winding of relay 114 to battery B. As has been previously mentioned the relay 114 is a re- 130

- versing relay which now, upon energizing, 5 operates to complete the circuit of generator R' over the trunk line conductor 180 instead of the conductor 181. Beginning at contact 10 spring 162 of relay 115 the generator circuit extends as follows: contact spring 162, contact springs 167 and 168, contact springs 134 and 135, contact springs 144 and 145, trunk line conductor 180 to bank contact 73, thence 15 by way of wiper 70, contacts of the switching relay 63, bank contact 34, spring 30, line conductor 12, and the ringers at substations A', A², A³, and A⁴ in parallel to ground. The 20 ringer at substation A' now responds, thereby notifying the calling subscriber that the 25 operation is proceeding satisfactorily.
- The operation continues as described until either the calling or called subscriber removes his receiver, the ringing relay 113 being 30 energized twice at every revolution of the interrupter shaft while the reversing relay 114 is energized at every other energization of the ringing relay, thereby ringing the 35 bells at substations A' and A⁵ alternately.
- When the called subscriber at substation A⁵ removes his receiver to answer the call, a circuit for the ring cut-off relay 106 is completed which, in case ringing relay 113 is not energized, extends as follows: 40 ground at G²⁰, contact springs 139 and 138, and contact springs 147 and 148 to trunk line conductor 181, thence over previously traced path to line conductor 11, thence by way of the receiver and transmitter of substation A⁵ to line conductor 12, thence over previously traced circuit to trunk line conductor 180, thence by way of contact springs 145 and 144, contact springs 135 and 136, and winding 109 of relay 106 to battery B. 45 In case the ringing relay is energized the trunk line conductor 181 will be grounded at G¹⁷ via the previously traced circuit of generator R': Hence, in this instance, ground at G¹⁷ will be substituted for ground G²⁰ in the above traced circuit, and in addition the battery end of the circuit, instead of passing direct from contact springs 135 and 136 of the ringing relay to the winding 109, will extend as follows: contact springs 135 and 134, contact springs 168 and 169, and winding 109 of relay 106 to battery B. 50 In case the reversing relay 114 is energized the circuit for the ring cut-off relay 106 will be the same as in the condition just mentioned except that the trunk line conductors 180 and 181 are reversed as regards their connection to ground and battery, respectively.
- In any case, it will be seen that when the 55 receiver is removed at substation A⁵, a circuit will be completed for the ring cut-off relay 106. Upon attracting its armature, relay 106 locks itself over the following circuit: ground at G¹⁵, off-normal contact 140, contact springs 142, and winding 110 to battery B. At the same time a circuit for the private magnet 108 is closed as follows: ground G¹⁵, off-normal contact 140, contact springs 141, and winding of private magnet 108 to battery B. The private magnet, upon energizing, disconnects the wipers 121 and 122, respectively, from relays 114 and 115. As a further result of the energization of the ring cut-off relay 106 the circuit of the switching relay 112 is broken 70 at contact springs 131. Upon deenergizing, the switching relay 112 restores the original circuit by which the trunk line conductors 180 and 181 are again extended to the double-wound line relay 100. The line relay 100 accordingly energizes as before, except that the loop includes substation A⁵ instead of substation A', and upon attracting its armature, again completes the circuit of the slow-acting release relay 101 over the 80 original path.
- The ringing operation has now been stopped. Being apprised thereby of the fact that the wanted subscriber has answered, the subscriber at substation A' will 85 now remove his receiver also, and is then able to converse with the subscriber at substation A⁵ as desired. Current is supplied to the two transmitters in parallel from the 90 windings of the line relay 100, while the 95 voice currents take the path shown in heavy lines.
- When the conversation is finished both 100 subscribers will hang up their receivers. When the last receiver is replaced the circuit of the line relay 100 is broken, which 105 relay therefore deenergizes to break the circuit of the slow-acting release relay 101. Upon deenergizing, the release relay 101 closes a circuit for the release magnet 111 110 in the usual manner, whereupon the frequency selector F is restored to normal position, the release magnet circuit being opened at off-normal contact 140' as the shaft reaches its lowest position. As a further 115 result of the deenergization of the release relay 101, ground G¹⁰ is removed from the holding circuit over which the switching relay 63 and the holding winding 17 have been maintained energized. It follows 120 therefore that the selector E and the line switch C are restored to normal position in the usual and well known manner, whereupon all the apparatus used will be ready for another call.
- I will now consider briefly a few other possible calls that the operation may be 125 thoroughly understood. Assuming that the subscriber at substation A⁵ desires to ring the subscriber at substation A⁶, we find by consulting the chart (Fig. 3) that the required telephone number is 045. The calling subscriber will therefore proceed to operate his calling device in accordance with this number whereby the wipers 123 and 124 130

are brought into engagement with the fifth set of contacts in the fourth level and the wipers 121 and 122 are brought into engagement with the fifth set of contacts of 5 the ninth level. That is assuming that the frequency selector F is the one used; it is understood, of course, that there are a plurality of such switches all accessible to calls in common. Now it will be seen that the 10 lower bank contact 4 up and 5 in is connected to the generator R', which is the generator to which the ringer at substation A⁵ responds; while the upper bank contact 4 up and 5 in is connected to the generator R² 15 which is the generator to which the ringer at substation A⁶ corresponds. It will be observed, further, that the lower bank contact 9 up and 5 in, with which the wiper 122 is in engagement, is connected to conductor 152 20 extending to interrupter I². And lastly it will be seen that since relay 114 is deenergized the middle spring 162 of relay 115 is connected via a path previously traced to the line conductor 11 from which the ringers at substations A⁵ and A⁶ are connected to ground. Now it will be clear that as the 25 interrupter shaft revolves the ringer relay 113 will be energized twice for each revolution of the interrupter I' while the relay 115 will be energized at every other energization 30 of the ringing relay or once per revolution of interrupter I². As a result first generator R' and then generator R² is connected to line conductor 11 whereby the two substations are signaled alternately. 35

Assuming now that substation A' is calling substation A², in which case the upper and lower sets of wipers will have been advanced, respectively, to the third contact set 40 in the ninth level and the third contact set in the fourth level, the operations are the same as in the last case, with the addition that the reversing relay 114 must now be operated at each energization of the ringing 45 relay 113, for the ringers at these substations are connected from line conductor 12 to ground. An inspection of the bank wiring will now show that a conductor 151, a branch of conductor 150, extends from 50 interrupter I' to the upper contact of the set 9 up and 3 in, which in the case of contact set 9 up and 5 in was vacant. Now as the interrupters revolve, the relays 113 and 114 are energized simultaneously twice at each 55 revolution of interrupter I' while relay 115 is energized once per revolution as before. This operation results in the alternate connection of generators R' and R² to the line conductor 12 whereby the substations A' and 60 A² are signaled alternately.

One more case will be considered—the case where the subscriber at substation A' is calling the subscriber at substation A⁶. The telephone number to be called is 022, resulting in the selection of the second sets of

contacts in the second and seventh levels. From an inspection of the bank wiring it will be seen that the upper and lower contacts of the second set in the second level are connected, respectively, to generators R' and 70 R². It will be seen, furthermore, that the upper and lower contacts of the second contact set of the seventh level are connected, respectively, to the interrupters I² and I³. Also it should be noted that the live segments of the interrupters I² and I³ are staggered with respect to each other. It follows therefore that in a certain part of the revolution of the interrupters the relays 113 and 75 114 will be energized simultaneously, followed later by the simultaneous energization of relays 113 and 115. In the first case generator R' will be connected to line conductor 12 to operate the signal at substation A' while in the latter case generator R² will 80 be connected to line conductor 11 to operate the signal at substation A⁶.

Since all the remaining combinations shown on the chart fall within one or the other of the cases already described, it is 85 thought that the circuits can be traced readily enough without further explanation.

While I have shown the circuits in the preferred form, they are susceptible to modifications to provide for other conditions. In addition it is to be noted that the wiring of the frequency selector bank as shown is largely an arbitrary arrangement. Care has been taken, however, to prevent the crossing together of generators by so arranging the 90 bank wiring that whenever two adjacent contacts are in use they are both connected to the same generator.

Having fully described and illustrated my invention, what I consider to be new and desire to have protected by Letters Patent will 95 be pointed out in the appended claims.

What I claim as my invention is:

1. In a telephone system, a party line provided with substation ringers connected 100 from opposite sides of said line to ground, a calling terminal and a called terminal for said line, ring-back apparatus at the exchange, means for extending a connection from said line to said ring back apparatus 110 via said calling terminal, and means for operating said apparatus to project ringing current back over said calling terminal to the calling line to enable one party to selectively signal the other parties on the same 115 line.

2. In a telephone system, the combination with a party line provided with substation ringers connected from opposite sides of said line to ground, of a plurality of grounded 120 ringing current generators at the exchange, and automatic means controlled over said line for connecting either conductor thereof to the ungrounded pole of any generator.

3. In a telephone system, a party line, 125

- substation ringers connected from opposite sides of said line to ground, and a ring-back apparatus for enabling one party on said line to call another on the same line, said 5 5 ring-back apparatus comprising means for transmitting ringing current first over one side of said line and then over the other.
4. In a telephone system, a party line, substation ringers connected from one side of 10 said line to ground, and a ring-back apparatus for enabling one party to call another on the same line, said apparatus comprising means for transmitting in alternation two different kinds of ringing current over the 15 ringer side of said line.
5. In a telephone system, a party line, substation ringers connected from opposite sides of said line to ground, a plurality of grounded ringing current generators for supplying 20 ringing currents of different character, and subscriber controlled means for selecting and connecting any one of said generators to either side of said line.
6. In a telephone system, a party line, a 25 calling terminal for said line and a called terminal for said line, a ring-back apparatus for enabling one party to call another on the same line, means for extending a connection from said line to said ring back apparatus, 30 said apparatus comprising means for signaling the stations on said line by projecting ringing current back over said calling terminal and over one side of said line and ground, and also comprising means operated 35 over the two sides of said line in series for stopping the signaling operation.
7. In a telephone system, a line, an automatic switch, a plurality of generators, means for operating said switch over said 40 line to select two of said generators, a conductor, means for connecting said conductor to either selected generator separately, and means for connecting said conductor to either side of said line separately.
- 45 8. In a telephone system, a line, an automatic switch, a plurality of generators, means for operating said switch over said line to select any one of said generators, and means for connecting the selected generator 50 to either side of said line separately.
9. In a telephone system, a line, an automatic switch, a plurality of generators, means for operating said switch over said line to select any two of said generators, and 55 means for connecting the said generators in alternation to one conductor of said line to the exclusion of the other conductor.
10. In a telephone system, a subscriber's line, a plurality of ringing generators for 60 supplying ringing currents of different character, and means including a switching device controlled over said line whereby a subscriber thereon may select at his option any one of said generators separately or any two 65 of said generators simultaneously.
11. In a telephone system, a subscriber's metallic line circuit, substation ringers connected from each side of said circuit to ground, a plurality of grounded ringing currents of different character, an automatic switching device for selecting any one of said generators, and means for connecting the ungrounded pole of the selected generator to the two sides of said line circuit 70 alternately.
12. In a telephone system, a party line, substation ringers connected from each limb of said line to ground, a plurality of grounded ringing current generators for supplying 80 ringing currents of different character, an automatic switching device for selecting any two of said generators, and means for connecting the ungrounded poles of said generators alternately to one limb of said line. 85
13. In a telephone system, a party line, substation ringers connected from each limb of said line to ground, a plurality of grounded ringing current generators for supplying ringing currents of different character, an 90 automatic switching device for selecting any two of said generators, and means for connecting in alternation the ungrounded pole of one selected generator to one limb of said line and the ungrounded pole of the other 95 selected generator to the other limb of said line.
14. In a telephone system, a party line, a plurality of ringing current generators for selective signaling on said line, a plurality 100 of interrupters for controlling the signaling operation, and an automatic switching device controlled over said line for simultaneously selecting one of said generators and one of said interrupters. 105
15. In a telephone system, a party line, a plurality of ringing current generators for selective signaling on said line, a plurality of interrupters for controlling the signaling operation, and an automatic switching device controlled over said line for simultaneously selecting any two of said generators and one of said interrupters. 110
16. In a telephone system, a party line, a plurality of ringing current generators for 115 selective signaling on said line, a plurality of interrupters for controlling the signaling operation, and an automatic switching device controlled over said line for simultaneously selecting two of said generators and two of 120 said interrupters.
17. In a telephone system, party lines, a plurality of ringing current generators for selective signaling on said lines, controlling circuits of different character for controlling 125 the signaling operations, and subscriber controlled means for simultaneously selecting one of said generators and one of said controlling circuits.
18. In a telephone system, a party line, 130

- substation signals connected in different relation to said line, ringing current generators and mechanism for connecting the same to said line, controlling circuits of different 5 character corresponding to the different arrangements of said signals for controlling said mechanism, and subscriber controlled means for selecting the proper controlling circuit.
- 10 19. In a telephone system, a line, a plurality of ringing current generators, an automatic switching device controlled over said line for selecting one of said generators and for connecting one conductor of said line 15 thereto, a relay for controlling said connection connected to the other conductor of said line, and a second relay for reversing the said line conductors as regards their connection, respectively, to the selected generator 20 and the said first relay.
20. In a telephone system, a party line, substation ringers connected from opposite sides of said line to ground, and a ring-back apparatus for enabling one party on said 25 line to call another on the same line, said ring-back apparatus comprising two or more relays for causing ringing current to be transmitted first over one side of said line and then over the other.
- 30 21. In a telephone system, a party line, substation ringers connected from one side of said line to ground, and a ring-back apparatus for enabling one party to call another on the same line, said apparatus comprising 35 a plurality of relays for controlling the application of two different kinds of ringing current to the ringer side of said line alternately.
22. In a telephone system, a line, an automatic switch, a plurality of generators, means for operating said switch over said line to select two of said generators, a conductor, a relay for connecting said conductor to either selected generator separately, and 45 another relay for connecting said conductor to either side of said line separately.
23. In a telephone system, a line, an automatic switch, a plurality of generators, means for operating said switch over said 50 line to select any one of said generators, and means for connecting the selected generator to either side of said line separately while
- said switch remains in an operated condition.
24. In a telephone system, a line, an automatic switch, a plurality of generators, means for operating said switch over said line to select any one of said generators, and for connecting the selected generator to either side of said line separately. 55 60
25. In a telephone system, a line, an automatic switch, a plurality of generators, means for operating said switch over said line to select any two of said generators, and means comprising two or more relays for connecting the said generators in alternation to one conductor of said line to the exclusion of the other conductor. 65
26. In a telephone system, a subscriber's metallic line circuit, substation ringers connected from each side of said circuit to ground, a plurality of grounded ringing current generators for supplying ringing currents of different character, an automatic switching device for selecting any one of said generators, and electromagnetic means for connecting the ungrounded pole of the selected generator to the two sides of said line circuit alternately. 70 75
27. In a telephone system, a party line, substation ringers connected from each limb of said line to ground, a plurality of grounded ringing current generators for supplying ringing currents of different character, an automatic switching device for selecting any two of said generators, and electromagnetic means for connecting the ungrounded poles of said generators alternately to one limb of said line. 80 85
28. In a telephone system, a party line, substation ringers connected from each limb of said line to ground, a plurality of grounded ringing current generators for supplying ringing currents of different character, an automatic switching device for selecting any two of said generators, and automatic means for connecting in alternation the ungrounded pole of one selected generator to one limb of said line and the ungrounded pole of the other selected generator to the other limb of 90 95 said line. 100

Signed by me at Chicago, Cook county,
State of Illinois, this 31st day of July, 1916.
